TIRE

Bruce D. Caulkins, Mountainside, N.J., assignor to Atlas Supply Company, Newark, N.J.

Filed May 28, 1959, Ser. No. 56,112

Term of patent 14 years

(Cl. D90—20)

Fig. 1.

Fig. 1 is a perspective view of a tire showing my new design, it being understood that the full line portions of the design are repeated throughout the circumference of the tire shown by means of broken lines;

Fig. 2 is a fragmentary top plan view thereof on an enlarged scale;

Fig. 3 is a transverse cross-sectional view thereof taken on line 3—3 of Fig. 2; and

Fig. 4 is an enlarged side elevational view thereof, the opposite side being substantially like the side shown.

The dominant features of my design reside in the full line portions of the drawing.

I claim:

The ornamental design for a tire, as shown and described.
